GRAVER HOLDER

William Marsheck, Baltimore, Md.

Application November 12, 1940, Serial No. 365,273

3 Claims. (Cl. 90—24)

(Granted under the act of March 3, 1883, as
amended April 30, 1928; 370 O. G. 757)

The invention described herein may be manufactured and used by or for the Government of the United States for governmental purposes without the payment to me of any royalty thereon in accordance with the provisions of the act of April 30, 1928 (Ch. 460, 45 Stat. L. 467).

This invention pertains to holders and supports designed to facilitate the use of gravers, burins, groovers and similar instruments in engraving lines on glass negatives, or plates of metal, fiber or other material.

The instrument is of particular utility and advantage for engraving map plates, the engraved lines of which must be acute and uniform for distinction. In engraving road lines, for instance, it is highly desirable that they consist of minute parallel lines of precise uniformity.

Heretofore the engraver has had to depend upon his manual skill, in the manipulation of engraving instruments, for the perfection of minute engravings. The present invention aims to relieve the engraver of the tiring, straining and exhausting efforts necessary to effect perfection in engravings, whereby to render his manual skill less exacting and his engravings more uniform, precise and flawless than is possible by manual skill mechanically unaided.

An aim of the invention is to provide a holder for engraving instruments having suitable supporting elements capable of adjustment whereby to simulate the various positions or angles of the human hand when engraving, and, when the desired angularity has been determined with respect to the material to be engraved, the engraving tool will remain constantly in the desired position with respect to the material and the degree of cut to be made therein.

Generally, the improved device comprises a support, means for adjusting the angular relationship of the support with respect to a predetermined surface, and means for adjustably securing a burin, graver or other engraving instrument to the support.

Further and other objects of the invention will be apparent from the following detailed description, the appended claims, and the accompanying drawing illustrating an embodiment having the characteristics of the invention and by which the same may be practiced.

Figure 1 of the drawing is a perspective view of an embodiment of the adjustable graver holder illustrating an operable application and position of an engraving instrument;

Figure 2, a plan view of the embodiment of Figure 1;

Figures 3 and 4, front and side elevations thereof, respectively; and

Figure 5, an inverted plan view thereof.

A practical embodiment of this invention, such as illustrated in the accompanying drawing, may comprise a table-like support 10 of any desired size and shape but preferably, though not necessarily, of a configuration whereby it may be firmly grasped and conveniently operated. For example, the illustrated embodiment is provided with a slightly concave portion 11 which may even be roughed, knurled or serrated, as indicated by reference 12, for receiving the finger tips and to provide sufficient traction to hold or grip the operator's fingers during the pushing operation of the device. Other indentations, such as 13 and 14 may also be provided in the edges of the table-like support for receiving, for example, the third finger and thumb, respectively, in a manner whereby the device may be firmly grasped and whereby pushing force may be conveniently applied for operation.

Practical means whereby the angularity of the table, with respect to the surface to be engraved, 25 may be adjusted suitably comprises, as shown, leg-forming screws 15 threaded through the table 10 and provided with lock nuts 16 for retaining adjustments. To facilitate the movement of the graver holder during operation, the leg-forming screws may be provided with smooth, rounded, and polished ends and if desired may even be provided with anti-friction means such as ball bearings 17. Such bearing points will not alone facilitate the free action of the device, but 35 prevent the leg ends from marring or destroying minute and detailed engravings and will prevent the legs from scratching or cutting into the surfaces to be engraved. The bearing ends of the legs should of course have a bearing surface of 40 such size as will bridge the average engraved groove, as it is passed thereover, so as not to cause a tilting of the table.

A practical arrangement whereby an engraving instrument may be adjustably carried by the 45 table may comprise, as shown, a pair of fixed jaw-like elements 18 and 19, which may be integral portions of the table and between which the blade of an engraving instrument 20 may be freely passed, tilted about its longitudinal axis, 50 and tilted horizontally, laterally, and vertically about a traverse axis to provide angular adjustments which may not be readily accomplished by adjustments of the table leg-forming screws 15.

55 To fixedly secure the engraving instrument be-

tween the jaws 18 and 19 and to retain the blade in desired angles to the surface of the plate to be engraved, one or more set screws 21, 22 and 23 may be carried by the jaw members in a manner whereby they may be adjustably projected from the inner faces of the jaws into gripping relation with the blade of an engraving instrument passed therebetween, and whereby the engraving instrument may be secured to the tiltable table 10 at any desired angle, within a pre-determined range, to the surface to be engraved.

Once the instrument is secured between the jaws 18 and 19 at the approximate desired angle, the legs may then be adjusted to place the cutting edge or edges 24 of the graver in perfect contact, or other desired angles, with the surface to be engraved. When the desired angle of contact or cutting has been determined and set, the legs may then be equally lifted, or shortened, to the degree to which it is desired to have the instrument cut into the plate. The adjustment, of course, may be in any other desired order, rather than in the sequence given.

The desirability of angular adjustments of engraving instruments is obvious to the engraver and angular adjustments are particularly desirable in the use of engraving instruments having a plurality of cutting points, such as shown in the drawings by character reference 24, for the engraving of parallel lines. The angle of the blade, to a large extent, determines the width and depth of the engraved grooves and with the aid of the present invention such angular relationships, of the instrument to the surface to be engraved, are not alone maintained but the depth of cutting is uniformly controlled for perfection in results.

With the aid of this instrument the operator is enabled to adjust the graver to the position of

angle required for the engraving of single or parallel lines of even and equal strength; secure the adjustment; and proceed to engrave close and intricate detail with no danger of the graver tilting out of position and without variation in the groove or groovers being cut.

Having described my invention and illustrated an embodiment whereby the same may be practiced, what I claim is:

- 10 1. In engraving devices the combination of a support, means for universally adjusting the angular relationship of the support and for adjustably elevating the support with respect to a pre-determined surface, and means for securing an engraving instrument to said support and adapted to be angularly adjustable thereon.
- 15 2. In devices of the class described, a manually controllable support, means carried by said support for securing an engraving instrument thereto, and means for universally adjusting the angle of the engraving instrument with respect to the surface to be engraved, said support being provided with means to create traction between the finger tips of an operator and the support during the manipulation of the device.
- 20 3. In devices of the class described, the combination of a support, means for adjustably elevating said support above a surface, said support having means for facilitating the manual gripping of the device during a sliding operation thereof, means for adjustably securing an elongated engraving instrument to said support, and means for adjusting an engraving instrument, of the character stated when carried by said support, rotatively about its longitudinal axis and also angularly with respect to a surface to be engraved.

WILLIAM MARSHECK.
